CLAIM

The ornamental design for a medical device for extra-corporeal heart and/or lung support, substantially as shown and described.

DESCRIPTION

FIG. 1 is a front view of a medical device for extra-corporeal heart and/or lung support comprising a new, original and ornamental design;

FIG. 2 is a rear view of the medical device for extra-corporeal heart and/or lung support comprising the new, original and ornamental design;

FIG. 3 is a left-hand side view of the medical device for extra-corporeal heart and/or lung support comprising the new, original and ornamental design;

FIG. 4 is a right-hand side view of the medical device for extra-corporeal heart and/or lung support comprising the new, original and ornamental design;

FIG. 5 is a top view of the medical device for extra-corporeal heart and/or lung support comprising the new, original and ornamental design;

FIG. 6 is a bottom view of the medical device for extra-corporeal heart and/or lung support comprising the new, original and ornamental design;

FIG. 7 is a top, front, right-hand side perspective view of the medical device for extra-corporeal heart and/or lung support comprising the new, original and ornamental design;

FIG. 8 is a front view of a medical device for extra-corporeal heart and/or lung support, with a protection bail shown in an extended position, comprising a new, original and ornamental design;

FIG. 9 is a top, front, right-hand side perspective view of the medical device for extra-corporeal heart and/or lung support, with the protection bail shown in an extended position, comprising the new, original and ornamental design;

FIG. 10 is a top, rear, right-hand side perspective view of the medical device for extra-corporeal heart and/or lung support, with the protection bail shown in an extended position, comprising the new, original and ornamental design; and,

FIG. 11 a top, rear, left-hand side perspective view of a medical device for extra-corporeal heart and/or lung support, with the protection bail shown in an extended position and with the addition of broken line environmental structure in the form of a module shown.

The broken lines are included for the purpose of illustrating portions of the medical device for extra-corporeal heart and/or lung support that forms no part of the claimed design.
